ORNAMENTAL DISPLAY DEVICE

Harry W. Tucker, Shaker Heights, Ohio, and
William S. McLeish, New York, N. Y.

Application December 23, 1932, Serial No. 648,531

6 Claims. (Cl. 40—148)

This invention relates to ornamental display devices and is particularly adapted to the display of pictures and the like.

An object of the invention is to provide an improved apparatus for displaying flat articles which will present a pleasing effect to the eye.

Another object is to provide an improved display apparatus which will be simple in construction.

10 Another object is to provide display apparatus which will be economical to manufacture.

Another object is to provide an improved display apparatus with which pictures or the like may be easily assembled.

15 Other objects will hereinafter appear.

The invention will be better understood from the description of two practical embodiments thereof, illustrated in the accompanying drawing, in which:

20 Figure 1 is a front elevational view of the invention applied to a picture held within a frame of somewhat modernistic design;

Figure 2 is a fragmentary sectional view to an enlarged scale taken on the line II—II of Figure 1;

25 Figure 3 is a perspective view to a reduced scale of some of the parts illustrated in Figures 1 and 2;

Figure 4 is a perspective view of a modified embodiment of the invention; and

Figure 5 is a view similar to Figure 3 of some of the parts illustrated in Figure 4.

In Figure 1 a picture frame is shown having a base 1 provided with two upwardly extending cylindrical posts 2 and 3, each recessed along the edge facing the other, as indicated at 4. Supported upon the base and having its edges held within the recesses are two panes of glass 5 with bevelled edges 6. Between these panes and 35 arranged back to back are pictures 7 and 8 inserted in a mat-like structure which is best illustrated in Figure 3.

This structure consists of pieces of paper, cardboard, cloth or other flexible material 9 and 45 10, shown as of rectangular configuration and provided with rectangular openings 9a and 10a, which pieces may be separate or integral or joined in any desired manner.

Secured to the backs of these pieces of material 50 are slightly smaller rectangular pieces of material or flaps 11 shown as held by adhesive 12 passing around three sides of their margins. The pieces 11 may conveniently be Cellophane or other thin sheet material and provide, between 55 themselves and pieces 9 and 10, pockets for the

reception of the pictures above mentioned, one of which is shown in Figure 3 as partially inserted into the pocket formed by pieces 10 and 11.

In practice, it is convenient to make the two flaps 11 of a single continuous sheet of material which may serve as a hinge between the two mat-like pieces 9 and 10. The flaps serve to assist in locating the pictures behind the mats and to retain them in position while being placed between the panes of glass, and while the entire assembly is being placed into the supporting structure.

The mat portions 9 and 10 are preferably colored and the two used in one frame may be of the same or different colors. The openings in the mats are smaller than the unbevelled portion of the glass panes, and the colored border about the picture, viewed through both the bevelled edges and the flat portion of the glass panes, produces an optical illusion, making the picture appear to be surrounded with a colored frame of considerable depth.

In Figures 4 and 5, mats 19 and 20 similar to those above described are provided, and secured to these mats is a layer of Cellophane or similar transparent material 21. A flap 22, which may also be of Cellophane, is provided with a central aperture 23, being secured to the sheet 21 about three sides.

The pictures may be inserted between the sheets 21 and 22, adjusted into position by friction of the finger reaching through aperture 23, and the edges of the mats inserted in slots 24 formed in a base 25 of any suitable material, such as wood, metal, glass or the like.

Slots 24 are disposed at a more acute angle than that formed by straight lines from the upper edge of the mats to the base of the slots, so that the sides of the mats 19 and 20 are bent into slightly concave form, producing sufficient friction between themselves and the sides of the slots to retain the parts in position. The bending also increases the pressure between the mats 19 and 20 and flaps 22, so that the pictures are firmly held in place.

While the flaps are shown as extending beyond the pictures in all directions, they can, of course, be cut away so that they are only strips, corner-shaped pieces or the like.

While we have described the illustrated embodiments of our invention in some particularity, obviously many others will readily occur to those skilled in this art, and we do not therefore limit ourselves to the precise details shown and described herein, but claim as our invention all 105 110

embodiments, variations and modifications coming within the scope of the subjoined claims.

We claim:

- 5 1. A display device comprising two sheets of flexible resilient material secured together along one edge by a substantially limp connection, openings therethrough, means for securing other sheets of material to said first mentioned sheets so that they may be viewed through the openings, and a supporting means common to said two first mentioned sheets and causing them to mutually flex each other.
- 10 2. A display device comprising two sheets of flexible resilient material, openings therethrough, means for securing other sheets of material to said first mentioned sheets so that they may be viewed through the openings, and a supporting means common to said two first mentioned sheets and causing them to bear upon each other to mutually flex each other.
- 15 3. A display device comprising two sheets of flexible resilient material secured together along one edge, openings therethrough, means for securing other sheets of material to be viewed behind the openings, and a supporting means common to said two first mentioned sheets and causing them to bear upon each other to mutually flex each other.
- 20 4. A display device comprising two sheets of flexible resilient opaque material secured together along their upper edges and having openings therethrough, a flexible flap secured to each sheet

throughout a portion of its periphery, each sheet and its associated flap being adapted to support an article to be viewed through the opening, and a base provided with slots adapted to receive the lower ends of said first mentioned sheets and disposed at an angle to maintain the sheets when inserted in flexed position.

5 5. A display device comprising two sheets of flexible resilient opaque material secured together along their upper edges and having openings therethrough, flexible transparent material secured to said sheets and overlying said openings, a flexible flap secured to each sheet throughout a portion of its periphery, and having an opening therethrough, and a base provided with slots adapted to receive the lower ends of said first mentioned sheets and disposed at an angle to hold the sheets in flexed position bearing upon each other.

6 6. A display device comprising two sheets of flexible resilient opaque material secured together along their upper edges and having openings therethrough, a flexible flap secured to each sheet through a portion of its periphery, and a base provided with slots adapted to receive the lower ends of said sheets and disposed at a more obtuse angle than would be assumed by the sheets if left free at their unattached edges and if these edges were separated by the same distance as are the slots.
